UNITED STATES PATENT OFFICE.

ROBERT SANFORD RILEY, OF WORCESTER, MASSACHUSETTS, ASSIGNOR TO RILEY STOKER CORPORATION, OF WORCESTER, MASSACHUSETTS, A CORPORATION OF MASSACHUSETTS.

STOKER-DRIVING MECHANISM.

Application filed April 22, 1922. Serial No. 556,015.

This invention relates to mechanical stokers of the underfeed type and particularly to improved driving mechanism for certain parts thereof. In such stokers 5 vision has been heretofore made for movable ash discharge or dumping plates at the rear of the stoker, such plates being given an oscillating or reciprocating movement through connections with the movable retort 10 side walls or with other movable fuel-engaging parts of the stoker.

It is at times desirable to operate certain of the stoker elements independently of other parts and to be able to stop the movement of 15 selected parts for a desired period.

Accordingly, it is the general object of my invention to provide improved mechanism for moving the ash discharge or dumping plates, by which mechanism they may be 20 driven or stopped independently of all other parts of the stoker and by which they may preferably be operated at different selected speeds. This mechanism permits the operator to control the ash discharge at will, 25 allowing the ash to accumulate if the bed of ashes is too thin and removing the ashes with greater or less rapidity when further accumulation is not desired.

It will be further understood that the high 30 temperatures encountered in modern furnace practice render it essential that a sufficient layer of ashes remain on the discharge plates and other metal parts of the stoker to protect them from the heat of the furnace. 35 This may be more easily accomplished with my improved arrangement of driving mechanism.

Two forms of my invention are shown in 40 the drawings, in which Fig. 1 is a longitudinal sectional elevation of a stoker embodying one form of my invention, with the walls and certain internal parts shown in section;

Fig. 2 is a perspective view of certain of 45 the ash discharge plates and parts of the actuating mechanism therefor;

Fig. 3 is a side elevation of the stoker, showing the driving connections for the discharge plate mechanism;

Fig. 4 is a sectional plan view taken along 50 the line 4-4 in Fig. 3;

Fig. 5 is a view similar to Fig. 1 but showing a second form of my invention;

Fig. 6 is a plan view of certain ash dis-

charge plates and parts of the driving mechanism therefor; and

Fig. 7 is a perspective view of the parts shown in Fig. 6.

Referring particularly to Figs. 1 to 4, I have shown an underfeed stoker which is in general of a usual type, comprising a hopper 10 from which the fresh fuel is forced through a casing or chute 11 by a ram or plunger, not shown, but actuated from a crank shaft 12 mounted in the upper part 60 of a speed changing gear box 13. A main power shaft 14 (Fig. 3) is indicated as extending transversely below the floor F and as being connected by sprockets 15 and 16 and a chain 17 to a driving shaft 18 in the 65 gear box 13.

The driving connections between the shaft 18 and the crank shaft 12 form no part of my present invention and for a further description thereof, reference is made to the 75 prior application of Irving A. Taylor, Patent No. 1,486,311, issued March 11, 1924. For the purpose of this application, it is sufficient to state that the handle 20 at the front of the gear box permits the operator 80 to connect the crank shaft 12 with the driving shaft 18 for rotation thereof at either of two different speeds.

The stoker further comprises the usual retort side walls 21 (Fig. 1) supporting tuyère 85 blocks 22 and preferably having over feed grates 23 associated therewith at the rear end of the retort. These side walls and overfeed grates are commonly provided with suitable driving connections to the crank 90 shaft 12 so that they may be regularly reciprocated during the operation of the coal feeding mechanism. These connections include bars 80 (Figs. 1 and 5) extending forward and supporting rods 81 slidable in 95 transverse openings in a cross pin 82 movable with the ram or plunger 83. A lost motion connection is thus provided by which reduced sliding movement may be given to the side walls. By reducing the lost motion, the 100 movement of the side walls may be increased.

Ash discharge or dumping plates 24 are mounted at the rear of the overfeed grates 23. These plates 24 are pivoted at their front ends to bars 25 mounted to slide in the 105 supporting framework of the stoker below the overfeed grates 23. The plates 24 are commonly of curved outline, with their

- under surfaces supported on rolls 26 at the rear ends of rack bars 27 also slidably supported in the stoker frame and engaged by pinions 28 on a cross shaft 29. The shaft 5 29 may be connected by a gear 30 (Fig. 3), pinion 31, sprocket wheel 32 and chain 33 to a sprocket wheel 34 provided with a hand wheel 35 by which the rack bars may be adjusted forward or rearward.
- 10 The slide bars 25 (Figs. 1 and 2) have pin and slot connections with arms 36 secured to a pair of cross shafts 37 and 38, the slide bars being connected alternately to different shafts. Segment gears 39 (Fig. 3) connect the shafts 37 and 38 and the shaft 37 15 is also provided with an arm 40 pivotally connected to a link 41.

A headed rod 42 is secured to the front end of the link 41 and extends through a 20 sleeve 43 mounted on a crank shaft 44. The crank shaft is preferably independently driven from the power shaft 14 in some convenient manner, as by a sprocket wheel 45, chain 46, sprocket wheel 47 and driving 25 shaft 48 which may be connected to the crank shaft 44 through speed changing gear mechanism of the type described in the above mentioned Taylor application, the change gear mechanism being controlled by a handle 50.

As the crank shaft 44 rotates, the sleeve 43 alternately engages the end of the link 41 and the head of the rod 42, thus intermittently moving the shafts 37 and 38 alternately in opposite directions. The extent 35 of movement of the shafts 37 and 38 may be increased by placing one or more collars 51 on the rod 42 to reduce the amount of lost motion.

40 With these connections it will be seen that the movements of the ash discharge plates 24 may be controlled by the handle 50 and that they may be reciprocated at a desired speed and to a desired extent independently 45 of the movements of all other parts of the stoker.

In Figs. 5, 6 and 7 I have shown a different form of driving mechanism. In these figures the ash discharge plates 60 are 50 provided with grate openings 61 to which air is supplied through the trunnions or bearings of the plates from an air chamber 62. This chamber is connected by a passage 63 to the main wind trunk 64 of the stoker, the air pressure in the chamber 62 being 55 controlled by a damper 65.

Slide bars 66 are provided for the plates 60 and alternate slide bars are provided with rack teeth on their adjacent sides engaging segment gears 67 loosely mounted 60 between the adjacent bars. Arms 68 on the gears 67 are pivotally connected to a bar 69 mounted to slide transversely of the retorts and connected by a link 70 to a crank arm 65 71 secured to a worm gear 72.

The gear 72 may be driven in any convenient manner as by a worm 73 on a shaft 74 connected by a sprocket wheel 75, and chain 76 to a sprocket wheel, not shown, at the front of the stoker where it may be mounted on a driven shaft corresponding to the crank shaft 44 in Fig. 3, and similarly driven through a gear box if desired. As the worm wheel 72 is rotated by the means indicated or by any other suitable driving connections, the bar 69 will be reciprocated and the slide bars 66 will be alternately moved in opposite directions by the segment gears 67. It should be noted that the gears 67 have no fixed centers but are moved bodily forward 75 and rearward a short distance in addition to their angular movements as the bar 69 is reciprocated.

With the arrangement of mechanism shown in either form of my invention, it 80 will be evident that the ash discharge plates at the rear of the stoker may be regularly oscillated or reciprocated entirely independently of the retort side walls and other parts of the stoker associated with the fuel feeding mechanism. This permits much greater flexibility in the operation of the stoker, and as previously stated, permits the operator to control his fire to much greater 85 advantage. The accumulation of ash or 90 refuse at the rear of the furnace may be held at any desired point, regardless of the rate of feed of the fuel or the rate of movement of the retort walls or overfeed grates.

Having thus described two forms of my 100 invention, it will be evident that other changes and modifications can be made within the spirit and scope of my invention as set forth in the claims and I do not wish to be otherwise limited to the details herein 105 disclosed but what I claim is:—

1. A stoker having, in combination, a retort, means to feed fuel thereto, movable ash discharge plates mounted at the rear of said retort, and separately controlled actuating 110 devices for said fuel feeding means and said discharge plates, said devices being driven from a common source of power.

2. A stoker comprising fuel feeding and distributing devices, ash discharge devices, actuating means for said feeding and distributing devices, driving means for periodically moving said ash discharge devices, and controlling devices by which said actuating means and said driving means may 115 be separately started and stopped.

3. A stoker having, in combination, a retort, a plurality of ash discharge plates movably mounted at the rear thereof, actuating means effective to feed and distribute fuel in said retort, and separately controlled driving means for said ash discharge plates, said driving means including devices for changing the speed of operation of said 125 plates.

4. A stoker comprising fuel feeding and distributing devices, ash discharge devices, actuating means for said feeding and distributing devices, driving means for periodically moving said ash discharge devices, and controlling devices by which said actuating means and said driving means may be separately started and stopped, and by which the speed of operation may be varied. 50
5. A stoker having, in combination, a retort, a plurality of ash discharge plates movably mounted at the rear thereof, actuating means effective to feed and distribute fuel in said retort, driving means for said discharge plates, and separate controlling devices for said actuating means and said driving means, said controlling devices including speed changing gear mechanisms by which different rates of movements may be attained. 60
6. A stoker having, in combination, a retort, a plurality of ash discharge plates movably mounted at the rear thereof, actuating means effective to feed and distribute fuel in said retort, and driving means for said ash discharge plates, controlling means separate from said actuating means, said driving means including devices for changing both the relative frequency of movement and the extent of movement of said plates. 70
7. A stoker having in combination, a retort, a plurality of ash discharge plates movably mounted at the rear thereof, actuating means effective to feed and distribute fuel in said retort, driving means for said discharge plates, said actuating means and said driving means having a common source of power, said actuating means for the feeding and distributing of fuel being separately controlled from the driving means for said discharge plates. 80
8. In a stoker, fuel feeding mechanism, a plurality of movable ash discharge plates, sliding bars to which said plates are connected respectively, a pair of shafts, one of said shafts having a driving connection with alternate sliding bars and the other of said shafts having a driving connection with the intermediate of said sliding bars, coacting gears mounted on said shafts for simultaneous movement in opposite directions and means to move said gears, said means and said mechanism being separately controlled. 85
9. A stoker having, in combination, a retort, means to feed fuel thereto, movable ash discharge plates mounted at the rear of said retort, actuating devices for said fuel feeding means and said discharge plates having a common source of power and independent controls. 65
10. A stoker having in combination, a retort with movable side walls, movable ash discharge plates at the rear of said retort, mechanism for moving said side walls and mechanism for moving said discharge plates, common power means for said mechanism and a separate control for each mechanism. 65
11. In a stoker, fuel feeding mechanism, a plurality of movable ash discharge plates, sliding bars to which said plates are connected respectively, a pair of shafts, driving connections from alternate of said bars to one of said shafts, driving connections from the intermediate of said bars to the other of said shafts, coacting gears mounted on said shaft for simultaneous movement in opposite directions, common power driven means to move said gears and said fuel feeding mechanism and independent controls for said means and said mechanism. 80
12. In a stoker, in combination, movable fuel feeding and distributing devices, a plurality of movable ash discharge plates, slide bars to which said plates are connected, and driving means for said slide bars, said driving means being controlled independently of said movable devices and being connected to oppositely reciprocate adjacent slide bars. 85

In testimony whereof I have hereunto affixed my signature.

ROBERT SANFORD RILEY.
